UNITED STATES PATENT OFFICE.

AXEL G. SANDBERG, OF WORCESTER, MASSACHUSETTS, ASSIGNOR TO HAROLD ORTEI,
OF BOSTON, MASSACHUSETTS.

COIN BOX FOR TELEPHONES.

Application filed February 8, 1922. Serial No. 535,368.

To all whom it may concern:

Be it known that I, AXEL G. SANDBERG, a citizen of the United States, residing at Worcester, in the county of Worcester and State of Massachusetts, have invented a new and useful Coin Box for Telephones, of which the following is a specification.

This invention relates to a box for use in reminding telephone users of the fact that telephone calls have to be paid for and at the same time for receiving the coins deposited for that purpose.

The principal object of the invention is to provide a device having the above mentioned characteristics which will be very inexpensive to make and maintain and will not involve any unnecessary or expensive features.

The invention also involves a novel way of mounting the parts of a coin box and at the same time connecting them together, and a simple and convenient way of providing for the detachment of the cover to permit access to the bottom of the box.

Further objects and advantages of the invention will appear hereinafter.

Reference is to be had to the accompanying drawings in which—

Fig. 1 is a side elevation of a coin receptacle constructed in accordance with this invention showing in dotted lines a telephone instrument to which it may be attached;

Fig. 2 is an elevation of the device looking in the direction of the arrow 2 in Fig. 1;

Fig. 3 is a side view of the cover;

Fig. 4 is a side view of the attaching bracket;

Fig. 5 is a similar view of the bottom of the box;

Fig. 6 is a plan of the box;

Fig. 7 is a plan of the bracket; and

Fig. 8 is a central vertical sectional view of the box assembled.

I have shown the coin box itself as consisting of a bottom 10 and a top 11. These two parts can be made of substantially the same shape so that they can be pressed up of sheet metal in the same set of dies, but

the top is provided with a slot 12 for receiving the coins which, of course, is not present in the bottom. Both of these parts 10 and 11 are formed of a general cylindrical form with a flat end and the other end open.

The open ends are flared out at the edges 55 to form a circumferential projection 13 having the cross section of a quarter circle.

On the side of the cover is riveted a plate 14 which is provided with words or lettering to show what the box is for and indicate the amount to be deposited. This also serves as a handle for use in manipulating the detachable portion, namely, the cover.

The bracket by which the box is attached to the telephone instrument consists preferably of a single piece of sheet metal doubled on itself to form a circular collar 20. The ends are brought into parallel relation to each other to form two arms 21 close to each other, which can be securely attached 70 together by screws or bolts 22. These arms are bent outwardly to form two semi-circular parts 23, together forming a collar for surrounding the neck of the telephone instrument to which it is to be applied, and 75 the ends are brought together at 24 to receive another bolt or screw 25 to fasten these parts.

In the formation of the circular collar 20 it is bent outwardly at the center to form 80 a circumferential rib 26. The inside of this rib, which constitutes a circumferential groove, is arranged to receive the two circumferential projections 13 when the two parts 10 and 11 are assembled with their 85 flaring edges in contact with each other.

When the bolts or screws 22 and 25 are tightened the two parts of the coin box are not only secured together but are securely mounted on the telephone instrument.

When it is desired to empty the box, the screws are loosened sufficiently to permit the detachment of the cover 11. In doing this the plate 14 can be used as a handle for manipulating it. The bottom 10 cannot be 95 removed as it is provided with a series of outwardly extending nicks or projections 29 which extend into corresponding depressions in the inside of the collar 20.

When the cover 11 is removed the fingers 100 can be inserted in the box 10 to remove the coins or the whole instrument can be turned upside down to empty them.

From this description it will be obvious that a very inexpensive device for the purpose intended is thus provided and that it will serve to hold any desired number of coins in accordance with its dimensions, and

also serve to remind the telephone users that they ought to pay for the service without necessitating any further reminder.

Although I have illustrated and described only a single form of the invention I am aware of the fact that modifications can be made therein by any person skilled in the art without departing from the scope of the invention as expressed in the claims.

10 Therefore, I do not wish to be limited to all the details of construction herein shown and described, but what I do claim is:—

1. As an article of manufacture, a telephone coin box comprising a substantially identical bottom and top closed at their opposite ends and open at their adjacent ends which flare outwardly and are in contact with each other, a sheet metal collar surrounding said adjacent ends and having a circumferential groove inside for receiving both flaring open ends of the box and cover, said collar having its two ends projecting from it radially and close together and having opposite semi-circular bends forming a space for receiving a part of a tele-

phone instrument, and means for clamping said ends together to secure the collar about the box and to secure it to a telephone instrument.

2. As an article of manufacture, a telephone coin box comprising an upper and lower portion having flaring openings at their adjacent ends adapted to be brought into registration with each other, and a collar provided with a circumferential rib thereon providing a similar groove inside for receiving said flaring ends, and provided with means for clamping said collar on the adjacent ends of the box to hold them in position with respect to each other, said bottom being permanently connected with said collar whereby it will support the top when the collar is loosened, and the top being removable and the top having a projection extending therefrom constituting a handle.

In testimony whereof I have hereunto affixed my signature.

AXEL G. SANDBERG.
